UNITED STATES PATENT OFFICE

WALTER F. STIMPSON AND WILLIS E. FINCH, OF LOUISVILLE, KENTUCKY; SAID FINCH
ASSIGNOR TO SAID STIMPSON

SCALE

Original application filed January 26, 1925, Serial No. 4,834. Divided and this application filed October 31, 1927. Serial No. 230,087.

Our invention relates to scales and more particularly to constructions designed for an enameled finish.

This application is a division of our co-pending application Serial No. 4,834 filed January 26, 1925.

In the present state of the art of scale construction it is usual to secure associated parts to each other by the use of screws or bolts.

Where, however, the parts of the scale are given a vitreous enamel finish the localized stresses produced by such screws or bolts frequently cause a chipping of the enamel and consequent marring of the finish. To avoid such defect, we have designed a construction dispensing with such securing means and substituted therefor yieldable clips which may be readily engaged or disengaged without injury to the finish. These clips vary in construction according to the particular design of scale or the parts thereof which are removably secured but in each modification a resilient yieldable element is used in place of the screws or other fastening devices heretofore used.

In the drawings—

Figure 1 is a side elevation of a scale embodying our invention.

Figure 2 is a sectional plan view showing the platform and means for securing the same to the platform securing frame.

Figure 3 is a sectional view taken substantially on the plane indicated by line 3—3 in Figure 2, and

Figure 4 is a detail sectional view taken substantially on the plane indicated by line 4—4 in Figure 2.

In the drawings wherein like reference characters indicate like parts and by particular reference to Figure 1 it will be noted that there is illustrated a scale of the cylinder type comprising a platform frame A and a pedestal including the lower reduced portion B and the upper cylindrical portion C.

By particular reference to Figures 2 to 4

inclusive it will be noted that there is illustrated a scale platform R in engagement with the platform supporting frame S. These parts are secured to each other by providing the frame S with the radially projecting rounded lugs T for engaging the depending channeled flange U on the platform R. On the opposite side of the frame S there is arranged a spring bar V which is secured by depending posts or pins W passing through radially slotted lugs W' on said frame. The posts or pins W have sleeved thereon the springs W² which bear at one end on a clamping plate W³ and at their opposite ends against a nut W⁴. This bar V is of such extent that the opposite ends thereof may be engaged in the channeled flange U of the platform R and by then applying downward pressure upon said platform it may be snapped into engagement with the lugs T. This will securely attach the platform R to the frame S without the use of bolts, screws, or other equivalent fastening means.

By reason of the above construction the platform R may be secured to the platform S by yieldable resilient means which will not in any way injure the enameled finish.

It will be obvious that various changes in the specific details illustrated may be resorted to without departing from the spirit and scope of this invention and to this end reservation is made to make such changes as may come within the purview of the accompanying claims.

What we claim as our invention is:—

1. In a scale, the combination with a platform supporting frame, of an enameled platform for resting upon said frame and a resilient clip for securing said platform to said frame without pressure against the enameled surface.

2. In a scale, the combination with a platform supporting frame, of a platform provided with a depending channeled flange, radially projecting lugs on said frame for en-

gaging said channel on one side of the platform and a resilient bearing for engaging the channel on the opposite side of the platform permitting a snap engagement between said platform and frame.

3. In a scale, the combination with a platform supporting frame, of a platform provided with a channeled flange, and lugs and resilient means carried by said frame and engaging said channeled flange for detachably securing said platform to said frame.

In testimony whereof we affix our signatures.

WALTER F. STIMPSON.
WILLIS E. FINCH.
